US00D912761S

(12) **United States Design Patent** (10) **Patent No.:** **US D912,761 S**
(45) **Date of Patent:** **** Mar. 9, 2021**

(54) **TOILET RIM-BLOCK**(71) Applicant: **S. C. Johnson & Son, Inc.**, Racine, WI (US)(72) Inventors: **Steven A. Zach**, Waterford, WI (US); **Austin R. Barger**, Lafayette, CO (US)(73) Assignee: **S. C. Johnson & Son, Inc.**, Racine, WI (US)(***) Term: **15 Years**(21) Appl. No.: **29/694,186**(22) Filed: **Jun. 7, 2019**(51) **LOC (13) Cl.** **23-01**(52) **U.S. Cl.**USPC ..... **D23/208**(58) **Field of Classification Search**

USPC D23/208, 368; D28/8.1, 7-8, 20-22, 30, D28/63; D1/129, 101, 127, 100; D24/101; D32/40; D4/127, 129; 15/210, 244; 132/317, 320

See application file for complete search history.

(57) **CLAIM**

The ornamental design for a toilet rim-block, as shown and described.

DESCRIPTION

FIG. 1 is a top, front, right perspective view of a toilet rim-block showing our new design;
FIG. 2 is a front view thereof;
FIG. 3 is a rear view thereof;
FIG. 4 is a right side view thereof;
FIG. 5 is a left side view thereof;
FIG. 6 is a top view thereof; and,
FIG. 7 is a bottom view thereof.

1 Claim, 2 Drawing Sheets
